UNITED STATES PATENT OFFICE.

CHARLES W. LUMMIS, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

GAS-PRODUCER.

1,305,913.

Specification of Letters Patent.

Patented June 3, 1919.

Application filed January 27, 1915. Serial No. 4,650.

To all whom it may concern:

Be it known that I, CHARLES W. LUMMIS, a citizen of the United States, residing at Worcester, in the county of Worcester and

5 Commonwealth of Massachusetts, have invented a certain new and useful Improvement in Gas-Producers, of which the following, taken in connection with the accompanying drawings, is a specification.

10 The present invention relates to gas producers, and has particular reference to the construction of the shell, or fuel containing section, of devices of this class.

15 The high degree of heat prevailing in the gasifying chamber of a gas producer, particularly in the region or zone of the surface of the fuel bed, where the combustion of the fuel is most intense, necessitates the provision of a shell or fuel section, having, in 20 addition to the requisite heat resisting qualities, of a character to preserve the structural strength of the shell under the high temperatures to which it is subjected, the capability of minimizing the amount of heat lost by 25 radiation through the walls thereof from said chamber.

Firebrick, usually in the form of a lining incased within a sheet metal shell, and of sufficient thickness to minimize radiation 30 therethrough, has served to meet the requirements above stated, but its use in such form has been open to serious objection, as a result of its tendency to fuse with the ash and clinker, which latter adhere to the inner 35 surface of the lining in substantially unbreakable masses, seriously handicapping the efficient operation of the producer.

As an expedient to overcome this objection, producers have been built in which no 40 firebrick lining has been used, the wall of the shell consisting of spaced steel plates, providing for the circulation of water therebetween. It is found, however, that the water jacket thus formed takes too much 45 heat from the adjacently disposed fuel, which becomes comparatively cool, allowing the excessive permeation of the blast near the wall of the shell and the consequent dilution of the gas which has been formed in 50 the hotter portions of the fuel bed.

The present invention contemplates a shell which avoids the objections above noted to the use of firebrick linings and water jacketed metallic walls, the essential features of 55 the same being fully set forth in the follow-

ing description and illustrated in the accompanying drawing, in which the figure is a vertical sectional view of a portion of a gas producer constructed in accordance with my invention.

60 In the said drawing, the shell or fuel section 1 of the producer is shown in connection with an upper cover section 2, inclosing the gasifying chamber 3 between the outer walls of said sections 2 and 3 and the surface of 65 the bed of fuel in said fuel section. As shown, said sections are made separate and independent, the cover section 2 being supported by posts or standards 2' to enable, if desired, the mechanical rotation of the 70 fuel section without interfering with the means for delivering gas through a passage 4 leading from the cover section. The fuel section, in accordance with approved practice, flares outwardly from the bottom, the 75 wall of said section comprising, in part, sheet metal plates 5 and 6 suitably riveted or attached in any well known manner, to form the open ended structure shown in the figure.

80 In the present embodiment of the invention, the plates 5 define the flaring portion of the shell, and the plates 6 are extended vertically upward from the interior of the flaring portion to define a shell portion of 85 uniform diameter in the region or zone of the surface of the fuel bed, said two shell portions intersecting in a plane considerably below the extreme upper ends of the flaring plates 5. The shell thus defined by the 90 plates 5 and 6 has a firebrick lining, the portion 7 of said lining adjacent the plates 5 being of the thickness usually employed for the lower portions of ordinary brick lined producers. It is to be understood that 95 the lining in this locality is not subjected to the intense heat prevailing in the region of the surface of the fuel bed, and hence is not subjected to the deleterious effects of fusion of its fuel contacting surface. Above 100 the lining 7, and extending upwardly for incasement by the plates 6, a lining 8 is provided, which is of a thickness considerably less than that employed, in ordinary practice, for the producer walls in the region of 105 greatest heat. In accordance with the present invention this lining 8 is only about one-half as thick as the linings usually employed for the fuel bed surface region of the ordinary brick lined producers.

Extending vertically upward from the outer ends of the plates 5 are the plates 9, spaced from and surrounding the shell portion formed by the plates 6, and defining an 5 annular chamber or open trough 10, having parallel sides formed by the plates 6 and 9, and an inclined bottom 11 formed by portions of the plates 5. Said trough 10 forms a jacket space for the constant circulation of 10 a body of cooling water, surrounding the region or zone of greatest heat which is inclosed within the relatively thin firebrick lining 8, and in addition said body of water is in convenient position to receive an annular skirt or apron 12, depending from the cover section 2, to form a water seal against the escape of gases from the combustion chamber 3.

By the construction described above, the 20 over heating of the lining 8, to a point of fusion, is avoided, said lining being sufficiently thin to enable the cooling action of the body of water to be transmitted therethrough. However, the previously set forth 25 disadvantages incident to the use of a water jacketed shell are not present, since the interposed lining 8 between the jacket and the fire prevents the excessive cooling of the fuel lying immediately adjacent the wall of 30 the producer.

In other words, the provision of a relatively thin fire brick lining, around which a constant circulation of cooling water is maintained, results in a proper insulation 35 of the cooling agent or water jacket from the fire, the insulating means, however, being of a character, by reason of its thinness, to transfer or radiate to the cooling agent a sufficient amount of the heat to which it is 40 subjected, whereby the damaging effects of the heat upon the exposed surface of the same are avoided. The lining 8 is not subject to fusion upon its inner surface, and still the adjacently disposed portions of the 45 fuel are sufficiently removed from the influence of the cooling agent to prevent the impairment of the gasifying operation in the regions immediately adjacent the walls of the producer.

50 It is to be noted that the thickness of the lining 8 is dependent upon the coefficient of heat conduction of the material employed. With the ordinary grades of firebrick used for gas producer linings, it has been found 55 that with a lining 8 about four and one half inches thick, enough heat is abstracted by the surrounding water jacket to cool the

inner surface of the lining below the temperature where it slags with the ash. However, with material having a higher coefficient of heat conduction, a thicker lining 60 may be employed. The cooling water abstracts heat from the shell surrounding the lining, faster than if said shell were merely exposed to the air; consequently a lining of 65 sufficient thickness for the requisite structural strength may be employed.

I claim,

1. In a gas producer, a shell providing a 70 gas producing chamber, said shell comprising a water chamber open at the top and surrounding said gas producing chamber in the zone of greatest heat thereof, and an interposed lining of firebrick between said water chamber and the contents of said gas 75 producing chamber of sufficient thinness to permit the conduction of heat therethrough to said water chamber at a rate calculated to maintain the temperature below the fusion temperature of said firebrick. 80

2. In a gas producer, a sheet metal shell 85 inclosing a gas producing chamber, said shell comprising an outwardly flaring lower portion and a substantially vertical upper portion disposed within and intersecting said flaring portion below the upper open end thereof and below the zone of greatest heat within said chamber, a firebrick lining for 90 said shell portions, said lining being of reduced thickness in the region of said vertical upper portion, and an exterior wall attached to and extending vertically upward from the rim of said flaring portion to provide a water chamber surrounding said vertical portion. 95

3. In a gas producer, a water-jacketed shell inclosing a gas producing chamber, said chamber having a heat insulating lining 100 interposed between the water jacket and the zone of greatest heat within said chamber for preventing the chilling of the fire by said water jacket, said lining being of such thinness that the cooling effect of the water-jacket is sufficient to maintain the inner surface of said lining at a temperature below 105 that required to fuse said lining with the ash of the coal.

Dated this twenty-first day of January, 1915.

CHARLES W. LUMMIS.
